UNITED STATES PATENT OFFICE

EMMANUEL WAGGONER HEWARD, DECEASED, LATE OF TORONTO, ONTARIO, CANADA,
BY GERALDINE HEWARD, EXECUTRIX, OF TORONTO, CANADA

COUPLING DEVICE ADAPTED TO BE USED FOR ENGRAVING MACHINES

Application filed January 24, 1927. Serial No. 163,284.

This invention relates to improvements in coupling devices for engraving machines, and the object of the invention is to devise in an engraving machine using a manually operated lever and foot lever, a coupling for interchangeably connecting the manually operated lever and foot lever with the parts operated thereby, and it consists essentially of the arrangement and construction of parts as hereinafter more particularly explained.

Fig. 1 is a perspective view of the machine.

Fig. 2 is a transverse sectional view through the mechanism for adjusting the head block.

Fig. 3 is a vertical sectional view on line 3—3 Fig. 2.

Fig. 4 is a perspective detail of the slide lever interposed between the foot pedal rod and rod leading to the head block adjusting mechanism.

Fig. 5 is a sectional detail through Figure 4.

Figs. 6 and 7 are plan views of the head block and main casting on which the head block is slidably supported separated apart.

Fig. 8 is a sectional view on line 8—8, Figure 7.

Fig. 9 is a sectional detail showing the parts 15, 35 and 36 in the disengaged position, and

Fig. 10 is a similar view to Fig. 9 showing the parts 15, 35 and 36 in the engaged position.

In the drawings like characters of reference indicate corresponding parts in each figure.

1 indicates the main table of the machine supported upon legs 2 and 3.

8 is a bed plate base mounted and suitably secured upon the table 1. 9 is a main standard extending upward from the rear portion of the base 8 and extending forwardly to form a head block support 10 at each side of which are formed the guide ribs 10^x and 10°. 45 at each side of a central vertical groove 10¹. 11 is a shaft journaled in orifices 12 and 13 formed in the side walls of the recess 14°, the outer portion of which is threaded as indicated at 11^x (see Figure 2). 14 is a bearing plate secured to the portion 10 of the main

casting 9 and provided with an orifice 14^x through which the shaft 11 freely extends.

15 is a circular plate also supported freely upon the shaft 11. 16 is a plate secured to the plate 15 and locked by a set screw 16^x to the shaft 11 and having bearing contact with the plate 14. The plate 15 is provided with a peripheral lug 15^x to which a link rod 17 is pivotally secured.

18 is a link lever, the outer member of 60 which is provided with an undercut groove 18^x in which the inner member 19 slidably fits.

The opposite end of the link rod 17 is pivotally connected to the member 19 as clearly indicated at 20 in Figure 4.

The outer member 18 is provided with a stud 21 turnably mounted in the main standard 9.

22 is a lug extending from the member 18 to which the pedal link rod 23 is pivotally connected. 24 is a foot pedal mounted upon a bracket 25 and pivotally connected at 26 to the lower end of the link rod 23. 27 is a stop lug extending from the lower peripheral portion of the circular plate 15. 28 is a lug extending from the main standard 9 and provided with an internally-threaded orifice 28^x. 29 is a stop screw extending through the threaded orifice 28^x and engaging therewith and projecting therefrom so as to form an adjustable abutment against which the stop lug 27 normally bears. 30 is the operating handle of the screw 29, such screw being provided with a locking lever 31 threaded thereon and bearing against the end of the lug 28 so as to lock the screw 29 from longitudinal movement. 32 is a plate provided with a circular recess 33 in its front face.

The plate 32 is freely fitted with a central orifice in which is driven an internally-threaded sleeve or bushing screwed upon the shaft 11 as clearly indicated in Figure 2. The plate 32 is also provided with orifices 34 extending therethrough and containing pins 35 which are slightly longer than the length of the orifices so that their projecting ends engage the opposing faces of the plates 15 and 36 and thereby increase frictional contact.

36 is a plate which fits freely within the 100

recess 33 and upon the shaft 11. 37 is a nut threaded upon the outer end of the shaft 11 and provided with a handle 38. 39 is a handle extending from the plate 32. 40 is a head block provided with a slideway 41 slidable upon the guide ribs 10^x and 10^y. 42 is a rack formed in the base of the slideway 41 and adapted to mesh with the gear segment 43 secured upon the shaft 11 within the recess 14^y. 44 is a locking screw whereby the head block may be manually locked in any desired position.

When the device is operated by the foot lever the manually operated lever 39 does not work back and forth, the action from the foot lever passes through the link rod 17 to the lug 15^x upon the disc 15 which is reciprocated concentric to the shaft 18 free of the disc 32 and, therefore, turns the member 16 so as to rotate the shaft 11 and operate the head block. When the plate 32 is locked to the disc 15 by means of the pins 35 forced into frictional engagement between the discs 36 and 15 by means of the nut 37 when screwed against the disc 36 and the manually operated lever 39 employed, the shaft 11 is turned through the discs 32 and 15 and plate 16, the foot lever operating freely up and down. When the shaft 11 is turned either by the hand operating handle 39 or by operating the foot pedal 24 the head block is raised or lowered as desired.

The bed plate upon which the work is supported is then adjusted in the usual manner by turning the lead screws 45 and 46 to carry the members of the slide rest in a longitudinal or transverse direction according to common practice. After this adjustment is accomplished the foot pedal 24 drops carrying the cutting tool again into engagement with the work, such downward movement being limited by the lug 27 of the plate 15 engaging the end of the stop screw 29.

If it is desired to adjust the head block manually the lever 38 is operated to turn the nut 37 so as to carry it against the plate 36 and thus make the connection between the plates 36, 32 and 15. When this is done the adjustment is made manual by the operator grasping the handle 39 and directly turning the plate 32 connected to the plate 15 by the clutch pins 35 thereby turning the shaft 11 and operating the quadrant 43 and rack 42 as above described.

55 64 is the head spindle journaled in bearings 65 and 66 and suitably driven.

What is claimed as the invention is:

In a device of the class described, the combination with a threaded shaft, of a disc secured thereto, a disc having a recessed outer face and bearing at its opposite face against the secured disc and having orifices extending therethrough, means for freely mounting the recessed disc upon the threaded shaft, 65 pins freely held in the orifices to be slid longi-

tudinally into engagement with the secured disc and to project slightly at their opposite ends into the aforesaid recess, a disc fitting within the recess and turnable freely around the shaft, and a clamping device for forcing the disc of the recess against the pins and the pins against the secured disc at the opposite end of the pins.

GERALDINE HEWARD,
*Executrix of Emmanuel Waggoner Heward, 75
Deceased.*
